Patented Apr. 19, 1927.

UNITED STATES PATENT OFFICE.

EDWIN ELLIOTT AND HAROLD ROEBUCK, OF SHANGHAI, CHINA.

THREAD GUIDE FOR SPINNING, TWISTING, AND WINDING MACHINERY.

Application filed September 23, 1925, Serial No. 58,110, and in Great Britain January 13, 1925.

This invention relates to a thread guide for spinning, twisting and winding machinery and has for its chief object to introduce an improved construction which will reduce friction and consequent breakages of thread, be much more durable and be capable of receiving a more efficient adjustment than the ordinary thread guide which is usually constructed from a length of wire coiled immediately of its length and terminating in a downwardly extending finger, one portion of the wire being flattened and threaded and passed through an oblong or non-circular hole in a hinged lappet and provided with a nut by which the position of the eyelet can be adjusted.

The invention consists in the combination with an eyelet or guide, of a roller over or round which the thread is taken so that the pull of the thread comes upon the roller instead of upon the eyelet or stationary part of the guide whereby friction and breakages are materially reduced. The guide finger or snarl catcher is advantageously made separately from the other portion of the guide and is capable of having its angular position adjusted in relation thereto.

In the accompanying drawings:—

Fig. 1 is a side elevation, and Fig. 2 a plan of a thread guide constructed according to this invention.

Fig. 3 is a similar view to Fig. 2 showing the shaft on which the roller is mounted broken and moved to one side to illustrate the construction of the device.

A indicates the thread guide, B the roller, C the snarl catcher, and D the hinged lappet.

The thread guide A is constructed from a length of wire which is bent upwardly at a and secured to a block a^1 having a square hole a^2 . The shank a^3 of the thread guide is threaded to receive nuts a^4 by which it is secured to the lappet D. The snarl catcher

C comprises a length of wire bent at right angles and one portion of such wire acts as an axle for the roller B and is formed with a squared portion at c to enter the square hole in the block a^1 and the end of the wire is threaded at c^1 . The roller B is first placed in position on the axle portion and the square portion is then passed through the square hole in the block a^1 . A washer c^2 is now placed over the threaded end of the arm which is then secured to the block a^1 by a nut c^3 and lock nut c^4 . The roller may be fitted with a loose sleeve to reduce friction and it may be constructed from any appropriate metal, glass, porcelain, or the like. The guide so formed can be attached either to a metal or wood lappet.

What we claim as our invention and desire to secure by Letters Patent in the United States is:—

1. A thread guide comprising a shank formed with a loop having a cranked end terminating in a perforated block, a roller mounted on an axle having one portion adapted to fit the perforated block and another portion bent at right angles and constructed to act as a snarl catcher, and means for securing the axle portion to the block.

2. A thread guide comprising a shank formed with a loop having a cranked end terminating in a block perforated with a non-circular hole, a roller mounted on an axle having one portion shaped to fit the non-circular hole and another portion bent at right angles and constructed to act as a snarl catcher, and means for securing the axle portion to the block with the snarl catcher in any adjusted position.

In testimony whereof we affix our signatures.

EDWIN ELLIOTT.
HAROLD ROEBUCK.
